JOHN KEANE, OF NEW YORK, ASSIGNOR TO HIMSELF AND GEORGE H. BROWN, OF MILBROOK, WASHINGTON HOLLOW, NEW YORK.

Letters Patent No. 90,453, dated May 25, 1869

IMPROVEMENT IN WATER-CLOSET APPARATUS.

The Schedule referred to in these Letters Patent and making part of the same.

To all whom it may concern:

Be it known that I, JOHN KEANE, of the city, county, and State of New York, have invented a new and useful Improvement in Water-Closet Apparatus; and I do hereby declare that the following is a full, clear, and exact description thereof, which will enable others skilled in the art to make and use the same, reference being had to the accompanying drawings, forming part of this specification.

This invention relates to improvements in apparatus for governing the flow to and from the basins of water-closets, whereby the water-valve is worked automatically, and regulated by a retarding-cylinder; and

The invention consists in the construction, arrangement, and combination of parts, as hereinafter more fully described.

In the accompanying drawings—

Figure 1 represents a side view of the apparatus, partly in section.

Figure 2 is a top or plan view.

Figure 3 is a sectional view of the retarding-cylinder detached.

Figure 4 is a view of the slide and slotted stand, looking at the end of the apparatus from the left.

Similar letters of reference indicate corresponding parts.

A is the water-supply cock.

B is the supply-pipe.

C is the discharge-pipe.

The cock A is operated by means of the pinion-wheel D on the end of the cock, and the sector-rack E on the end of the lever F.

This lever has its fulcrum at g, on the central stand H.

I is a cylinder, which contains a spiral spring, J, the tendency of which spring is to throw up the end of the lever K, which has its fulcrum on the same central stand H.

L is a weight on the lever K, and

m is a weight on the lever F.

N is an adjustable socket, placed in a slot in the lever K.

This socket receives the pressure from the seat (when the closet is used) by means of a rod, which is fixed to the under side of the seat.

The weight of the person thereon depresses the short end of the lever K, raising the weight L, and compressing the spiral spring J.

O is a vertical-slotted stand on the base P.

R is a slide, which moves up in the slot S with the lever F, and drops down by its own gravity.

When the lever K is forced down by the weight of the person using the closet, as before stated, it is caught and latched to the slide, which raises the other lever F by the projection t, which passes down be-

tween the projection u on the slide R and the weighted latch v, which is hung on a pivot at w.

While the pressure remains on the seat, (and on the lever K,) the lever F remains stationary or depressed, as seen in fig. 1, the two levers being connected by the catch by means of the slide before mentioned.

Now, if the pressure is removed by the person rising from the seat, the weight L and also the spring J would both act to throw up the short end of the lever K, and the long end of the lever F with the slide R. But this action is retarded by means of a piston in the cylinder x on the rod y, which is connected with the lever F at z, as seen in the drawing.

The cylinder x contains liquid; and to guard against evaporation, freezing, or congelation in cold weather, glycerine is used.

The cylinder is closed at each end, the piston-rod y working through a stuffing-box in the head.

In the detailed view, fig. 3, it will be seen that there is a channel, a, on the outside of the cylinder, which connects with the cylinder above and beneath the piston.

As the piston descends, the liquid is forced from beneath to the upper portion of the cylinder above the piston. As the piston is raised, the liquid is forced in the contrary direction, or from the top to the bottom portion of the cylinder, and so on alternately.

The time for the discharge of the liquid in either direction through the channel a is regulated by the cock b.

As seen in fig. 1, the sector-rack E is so placed that the elevation of the other end of the lever F will revolve and open the cock D.

This would cause a sudden rush of water into the basin of the closet, as the action of the lever would be instantaneous in rising and in opening the cock, were it not for the retarding-device already described.

The liquid in the retarding-cylinder acts not only to retard the flow of water, and thereby make the wash more complete, but as a cushion, to render the action of the levers soft and noiseless, and for preventing damage by any sudden concussion in any part of the apparatus.

As before stated, the left-hand ends of the levers F and K move together, and rise while the wash is taking place. This rising motion is fast or slow, according to the position of the cock b.

When the levers have been sufficiently elevated, or the wash sufficiently prolonged, the lever K is released from the lever F, in consequence of the peculiar arrangement of the projections t and u, in regard to the latch v.

It will be seen that while the slide R rises vertically with the projection u, the projection t rises on a circle, the radius of which circle is the distance of t from the fulcrum g. This deviation of t from a vertical line

carries it from the catch and releases the levers from the slide.

When this takes place, the weight *m* depresses the lever *F*, and gradually closes the cock, and gives the after-wash. It is governed in its back or closing movement by the liquid in the retarding-cylinder, as before described.

d is a drip-pan, for catching any water which may leak from the cock *A*.

D', fig. 2, is an arm, attached to the slide *R*, for raising the lever of the water-closet pan, and opening the same. When the slide is released by the latch *v*, it drops by its own gravity, and allows the pan to close by means of its lever-weight.

It will be seen that while the person is on the seat, the apparatus is at rest in all its parts. The pressure being removed, the cock is gradually opened, and the wash given while the pan of the water-closet is opened by means of the arm *D'*, the action in both cases being governed by the retarding-cylinder. When the latch is released, the cock is gradually closed, and the after-wash given, while the pan-lever is governed by the weight attached to its lever.

This apparatus may be placed either in front or rear of the water-closet basin, as may be deemed most advisable or convenient.

It is entirely automatic in its movements, and sure in its operation, durable, and not liable to get out of order.

Its advantages over any water-closet apparatus heretofore known are many, and must be obvious to all.

I claim as new, and desire to secure by Letters Patent—

1. A supply-water-cock or valve, *A*, operated by means of a pinion and sector-rack, in combination with a retarding-cylinder, arranged substantially as shown and described.

2. The combination of the levers *F* and *K* with the projections *t* and *u* and latch *v*, and the retarding-cylinder *x*, all constructed, arranged, and operating substantially as herein shown and described.

3. The combination of the arm *D'*, slide *R*, and latch *v*, substantially as and for the purpose specified.

4. The combination of the spring *J*, levers *F* and *K*, pin *D*, sector *E*, cylinder *x*, with its piston and rod *y*, and latch *v*, arranged and operating substantially as and for the purposes set forth.

JOHN KEANE.
